UNITED STATES PATENT OFFICE.

EMIL A. CLAUS, OF BROOKLYN, NEW YORK, ASSIGNOR TO PUBLIC SERVICE CUP COMPANY, OF BROOKLYN, NEW YORK, A CORPORATION OF NEW YORK.

VENDING-MACHINE.

1,239,884.

Specification of Letters Patent. Patented Sept. 11, 1917.

Application filed May 31, 1913. Serial No. 770,934.

To all whom it may concern:

Be it known that I, EMIL A. CLAUS, a citizen of the United States, and a resident of the city of New York, borough of Brooklyn, in the county of Kings and State of New York, have invented a new and Improved Vending-Machine, of which the following is a full, clear, and exact description.

This invention relates to vending machines and has reference more particularly to check or coin-controlled mechanisms for dispensing drinking cups or like articles. More specifically, the invention relates to a device of the class described which comprises a casing, a container for nested cups associated with the casing and serving to direct the cups into the casing, means for supporting the cups, and, when operated, for advancing the cups one at a time to a carriage, the carriage having means operable simultaneously with the cup-advancing means, for operating the carriage, to advance the cup thereon from the casing.

An object of the invention is to provide a simple and efficient vending machine for use with individual, paper drinking cups or like articles, which includes a check- or coin-control mechanism, which is compact in form, light in weight, and comprises comparatively few parts, which is so constructed that it is not capable, without difficulty, of unauthorized operation, and which when operated will dispense the contents one at a time only.

A further object of the invention is to provide a device of the class described in which the casing is normally associated with a supporting plate and has a door, in combination with means for preventing the removal of the casing from the plate, when the door is closed, the door serving to permit the removal of coins or checks which have been introduced into the casing, and to control the association of the casing with the supporting plate.

The invention consists in the construction and combination of parts to be more fully described hereinafter and particularly set forth in the claims.

Reference is to be had to the accompanying drawings forming part of this specification, in which similar characters of reference indicate corresponding parts in all the views, and in which—

Figure 1 is a vertical section of an em-

bodiment of my invention, showing the container for the nested cups broken away, the section being on line 1—1 of Fig. 2, illustrating the device in normal inoperative position;

Fig. 2 is a transverse section on line 2—2 of Fig. 1;

Fig. 3 is a vertical section on line 3—3 of Fig. 2;

Fig. 4 is a vertical section on line 4—4 of Fig. 1;

Fig. 5 is a similar section on line 5—5, Fig. 1;

Fig. 6 is a transverse section similar to Fig. 2, certain of the parts being shown in different positions;

Fig. 7 is a fragmentary section on the line 7—7, Fig. 1;

Fig. 8 is a section similar to Fig. 6, certain of the parts being shown in different positions;

Fig. 9 is a fragmentary section on the line 9—9 of Fig. 10;

Fig. 10 is a similar section on the line 10—10 of Fig. 9;

Fig. 11 is a fragmentary, vertical section showing certain details of construction of the cup-supporting and releasing mechanism;

Fig. 12 is a vertical section showing a lock for securing the cup-container with respect to the casing; and

Fig. 13 is a horizontal section on the line 13—13 of Fig. 12.

Before proceeding to a more detailed explanation of my invention, it should be clearly understood that while the device is particularly designed and adapted for use with individual drinking cups fashioned from paper or like material, and of truncated, conical form, it can also be employed in connection with other articles. Furthermore, while the mechanism is preferably coin or check-controlled, it may be so arranged that the contents can be dispensed at will without the introduction into the machine of a coin or check. The container for the cups is preferably a transparent cylinder disposed vertically above the casing, so that the cups are gravitationally directed into the casing, along a line substantially coincident with their longitudinal axes. However, this construction may be altered if desired, and with others of the details, forms no part of my invention. These may

be varied in accordance with the individual preference and special conditions without departing from the underlying spirit of the invention.

- 5 Referring more particularly to the drawings, I provide a box-like casing 3, having a partly cylindrical form, horizontally disposed at the lower front portion. At the top the casing has an annular opening surrounded by a flange 3^a upon which is mounted a ring 8, within the periphery of which is suitably secured a cylindrical container 7, of glass, or like material. The ring 8 has an upwardly extending flange surrounding the cylinder 7, and a downwardly extending flange which sits upon the flange 3^a.
 10 Rotatably mounted in the upper portion of the casing 3 on the studs 21 are one or more rotatable members or escapements 13 so disposed that they are located without the periphery of the cups as they pass into the casing. These escapements, preferably four in number as illustrated, are equally spaced circumferentially relative to the path of the cups in the stack 4 as they enter the casing. The escapements support the stack of cups, and when rotated are operable to support all of the cups except the lowermost one, which is permitted to escape 15 into the lower portion of the casing; and for this purpose the escapements are provided with blades 15 of helical or wedge form and which normally support the stack of cups. In addition each escapement has a blade or flange 14 which temporarily support the stack of cups. Each flange 14 is substantially normal to the axis 12 of the escapement. The operation of these devices is such that when they are simultaneously 20 rotated in one direction the stack of cups is transferred from the blades 15 to the flanges 14; and when they are rotated in the opposite direction, that is, to their original position, the lowermost cup remains upon the flanges 14 and the next adjacent cup to the lowermost is engaged by the blades 15, so that the stack of cups is thereupon supported by these blades, and the cup which has remained on the flanges 14 is then permitted to escape from the latter to a dispensing carriage.
 25 Within the casing is located a rotatable ring 22 provided with teeth 23 in engagement with pinions 24 which are rigidly associated with the escapements 13. The ring thus serves to rotate the escapements simultaneously as it rotates.
 Positioned below the ring 22 and concentric therewith is a ring 25 provided with a handle 26 projecting through a slot provided for the purpose in the casing. The handle 26 permits the manual operation of the ring 25. The latter is guided in its rotation by means of hubs 21^a of the pinion 24.
 30 The handle 26 is provided with a flange 27

adapted to engage an ear 28 of the ring 22 to return the latter to its initial or normal position after it has been displaced therefrom. The ring 25 is provided with a helical spring 29, one end of which is fixed to a post 30 70 of this ring and the other end to a post 31, rigidly carried by an apertured partition 17 of the casing. It serves to return the ring to its initial or normal position after it has been displaced from the same. The rings 22 and 25 have associated therewith check or coin-engaging means consisting of radial slots 42 and 43 respectively, located in their outer peripheries, so that when a coin is in common engagement with both slots the 80 ring 22 is operatively connected with the ring 25, and the latter serves to rotate the former as it is actuated. The partition 17 has an opening 44 therethrough which constitutes a passage for the coin into a receptacle 45 of the casing 3 (see Fig. 10). The opening 44 registers with the slots 42 and 43 when the rings 22 and 25 have in unison reached the limits of rotation.

Preferably the ring 22 is provided with a 90 coin guide 46 about the slot 42 which serves to guide the coin in an engagement with the slot 43 of the ring 25 therebelow. The ring 22 is further provided with a chute 47 adjacent the coin guide 46 for directing into 95 the cup receptacle below the ring any coin which may be deposited through the usual casing slot 35, while the machine is being operated by virtue of the presence of another coin in operative position, as shown in 100 Fig. 10.

In order to prevent the rotation of the ring 25 by means of the handle 26, in the absence of a ring-connecting coin, I provide a latch 48 pivoted by means of a suitable 105 pin 49 upon the partition 17. The latch is adapted to engage with a notch 50 in the ring 25. It is normally pressed into engagement with the notch by means of a spring 51. For lifting the latch out of engagement with this notch in the ring 25 when a coin is inserted, as is shown in Fig. 10, I provide on the latch a cam 52 for engagement with a lug 54 on the ring 22.

The casing 3 is mounted upon a vertical 115 wall or other support and for so supporting the casing and for locking it in position I provide a back plate 54 having screw holes 55 or other suitable means for fastening it to the guard (not shown). I provide in 120 addition, one or more casing supporting pins 56 having heads 57 and a locking pin 58. The back wall 59 of the casing is provided with slots 60 adapted to receive the pins 56, and, furthermore, with a slot 61 through 125 which the locking pin 58 projects. The latter is adapted to project into the check or coin receptacle or chamber 45, which is provided with a hinged door 62 mounted upon a pivot 63. The door has a groove alining 130

with slot 61, so that when the door depends vertically an upward movement of the casing will permit the pin 58 to pass through the groove and thus allow the removal of the 5 casing from the back plate 54 by the disengagement of the pins 56 from the slot 60.

Mounted within the chamber 66 of the casing 3 is a rocking or rotatable dispensing carriage 67. This has a normally upright 10 plug 68 which receives each cup as the same is discharged by the escapements 13. Upon the plug is a rib 69 which serves to minimize the surface contact between the cup and the plug when the same is discharged 15 from the plug. In this way any tendency to stick is obviated. The carriage 67 is mounted on trunnions 70 of the casing 3, and has a cylindrical wall 71 normally closing the discharge opening 72 of the casing. I pro- 20 vide on the ring 25 gear teeth 73 which mesh with a sector 74. The latter is pivoted at 75 on one side wall of the casing. Depending from the gear sector 74 is an arm 76 which terminates in an internal gear seg- 25 ment 77 engaging with the gear sector 78 of the carriage 67.

The ring 8 is locked to the casing 3 by means of a bolt 10 (see Figs. 12 and 13) 30 slidably received in a vertical slot 10^a of the ring 8. The rim 11 of the casing has a notch 10^b adapted to receive an end of the bolt 10. A set screw 11^a serves to limit the movement of the bolt. The spring 11^b within the slot 10^a normally projects the bolt out 35 of the slot 10^a. The bolt is provided with teeth 12^a engageable by a pinion 12^b of a key 13^a. The latter is so proportioned that it can be introduced into a keyhole 14^a of the ring 8, this keyhole being disposed adjacent the vertical slot 10^a and communicating therewith. A strip spring 14^b is located 40 in the slot and has the upper end laterally disposed and engaging the upper end of the bolt. The laterally disposed end of the 45 spring serves to engage the lower edge of the keyhole 14^a when the bolt 10 is withdrawn from the slot 10^a, thus preventing the spring 11^b from falling out of said slot. By this means the transparent container 7 is pre- 50 vented from accidental displacement on the casing 3.

The operation of the machine is as follows: A check or coin 39 having been deposited to engage the slots 42 and 43 of the 55 rings 22 and 25 respectively, the lever 26 is moved forward its full stroke, whereby through the instrumentality of the coin the gearing 22 is rotated in a clockwise direction and through the pinions 24 the escapements 60 13 are caused to rotate in a similar direction. Their blades 15 move out of supporting engagement below the flange of the lowermost cup 41, thereby lowering the stack of cups upon the flanges 14 which have been simul- 65 taneously rotated into supporting position.

It will be understood that these flanges are normally inoperatively disposed. Coincidentally, the gear teeth 73 in engagement with the sector 74, and through the internal segment 75 in engagement with the gear 78, 70 have rotated the carriage 67 from the position shown in Fig. 3 to that of Fig. 5. As the carriage has not yet been supplied with a cup this movement is ineffective to deliver an article. However, if the lever 26 is now 75 released it will be returned by the spring 29 to its initial position and the blades 15 will enter between the flanges of the cups 40 and 41, so that the cup 40 and those above it will be lifted and supported by the blades 15 and 80 the cup 41 will be released by the retreat of the flanges 14 and will pass to the plug of the carriage, which has returned to its end position. Thereafter, upon the insertion of 85 a coin in the slot 35 and the pulling forward of the lever 26, the carriage 67 will be rotated and the cup 4 discharged through the opening 72 of the casing. At the same time, another cup will be lowered into position upon the flanges 14, ready for delivery to 90 the carriage.

When the stack of cups in the retainer has been exhausted the key 13^a can be manipulated to unlock the ring 8 and permit the removal of the container and the supplying 95 of the machine with a new stack of cups.

From the above description it will be seen that the ring 22 which carries the escapement member constitutes the feed mechanism, which becomes operable when a coin is 100 inserted into the slots so as to bind the manually operated ring 25 to the ring 22. The feed mechanism delivers the cup to the dispensing mechanism after the dispensing mechanism has delivered the cup it had on 105 the plug 68.

Having thus described my invention, I claim as new and desire to secure by Letters Patent:

1. A device of the class described comprising in combination, means for guiding a stack of nested cups, a rotatable ring, a rotatable escapement, means for rotating said escapement from said ring, a second rotatable ring co-axial with said first-mentioned ring, check controlled means for rotating said first ring from said second ring, a latch for engaging with said second ring, and means on said first ring for lifting said latch from engagement with said second ring. 110

2. A device of the class described comprising in combination, means for guiding a stack of nested cups, a rotatable ring, means operably connected with said ring for dis- 115

charging cups from said stack, a second rotatable ring co-axial with said first-mentioned ring, check controlled means for rotating said first ring from said second ring, a latch for engagement with said second ring, and means on said first ring for lifting 120

125

130

said latch from engagement with said second ring.

3. A device of the class described comprising in combination, means for guiding a stack of nested cups, a rotatable ring, means operably connected with said ring for discharging cups from said stack, a second rotatable ring co-axial with said first-mentioned ring, check controlled means for rotating said first ring from said second ring,

10 a rotatable carriage for receiving and discharging the cups delivered from said stack, and means for rotating said carriage from one of said rings.

15 4. A device of the class described comprising in combination, means for guiding a stack of nested cups, a rotatable ring, means operably connected with said ring for discharging cups from said stack, a second rotatable ring co-axial with said first-mentioned ring, check controlled means for rotating said first ring from said second ring,

20 a latch for engagement with said second ring, means on said first ring for lifting said latch from engagement with said second ring, a rotatable carriage for receiving and discharging the cups delivered from said stack, and means for rotating said carriage from one of said rings.

25 5. A device of the class described comprising in combination, means for guiding a stack of nested cups, a rotatable ring, a second rotatable ring co-axial with the said first-mentioned ring, check controlled means for rotating the said first ring from said second ring, a rotatable carriage for receiving and discharging the cups, means actuated by said first ring for delivering cups one at a time to said rotatable carriage, a

30 hand lever for rotating said second ring, and means connecting said second ring with said carriage for rotating said carriage to discharge position by the forward movement of said lever.

45 6. A device of the class described comprising in combination, means for guiding a stack of nested cups, a rotatable ring, a second rotatable ring co-axial with said first-mentioned ring, check controlled means for rotating said first ring from said second ring, a rotatable carriage for receiving and discharging the cups, means actuated by said first ring for supplying cups one at a time to said rotatable carriage, a hand lever

50 for rotating said second ring, and means connecting said second ring with said carriage for rotating said carriage to discharge position by the forward movement of said lever, said cup delivery means being operable by the return movement of said lever.

7. In a vending machine, the combination of a container for a stack of nested cups, a casing associated therewith, an oscillating dispensing mechanism in the casing for delivering cups therefrom, a rotatably mounted

ed feed mechanism in the casing between the stack of cups and the dispensing mechanism, and check-controlled means for operating simultaneously the feed and dispensing mechanisms, mounted to rotate about the 70 axis of the feed mechanism.

8. In a vending machine, the combination of a container for a stack of nested cups, a casing carrying the container, a dispensing mechanism in the casing for delivering the 75 cups therefrom, a revoluble feed mechanism in the casing between the stack of cups and the dispensing mechanism, and check-controlled means co-axial with the feed mechanism and positioned between the feed and 80 dispensing mechanisms for operating the same.

9. In a vending machine, the combination of a container for a stack of nested cups, a casing associated therewith, a dispensing 85 mechanism in the casing for delivering cups therefrom, and a feed mechanism, including means for moving into the container the entire stack of cups with the exception of the one adjacent the feed mechanism, which is 90 delivered to the dispensing mechanism while the stack is so moved, said feed and dispensing mechanisms rotating on intersecting axes.

10. In a vending machine, the combination 95 of a container for a stack of nested cups, a casing associated therewith, a dispensing mechanism in the casing and adapted to deliver cups from the casing, a feed mechanism in the casing between the stack 100 of cups and the dispensing mechanism, said feed mechanism comprising a plurality of escapements mounted to rotate about axes parallel to the stack and positioned adjacent the outer periphery of the adjacent cups, 105 each of said escapements having a flanged portion and a helical blade portion adapted to move into the casing the entire stack of cups except the lowermost one, said flanged portion adapted to receive the lowermost 110 cup and clear the way for the same when the stack is raised by said helical flanged portion, whereby said cup is delivered to the dispensing mechanism.

11. In a vending machine, the combination 115 of a container for a stack of nested cups, a casing associated therewith, a dispensing mechanism in the casing adapted to deliver cups from the casing, and a feed mechanism in the casing between the stack 120 of cups and the dispensing mechanism, said feed mechanism comprising a gear mounted to rotate about the axis of the stack, escapements having pinions meshing with the gear, said escapements being positioned adjacent the outer periphery of the stack, each 125 of said escapements having a helical blade normally engaging the cup, and a flange portion adapted to receive the stack when the same is disengaged from the helical 130

blades, said helical blades becoming operative when the gear is rotated, the returning movement of said gear causing said helical blades to raise the stack of cups into the container, with the exception of the lowermost remaining on the flanges, said flanges adapted to clear the way for the said cup during the return movement of said escapement, whereby said cup is delivered to the dispensing mechanism.

12. In a vending machine, the combination of a container for a stack of nested cups, a casing associated therewith, a dispensing mechanism in the casing adapted to deliver cups from the casing, a feed mechanism in the casing between the stack of cups and the dispensing mechanism, said feed mechanism comprising an internal gear mounted to rotate about the axis of the stack, a plurality of escapements adjacent the outer periphery of the cups at the feed mechanism, said escapement having pinions meshing with the internal gear, each of said escapements having a helical blade adapted to move the entire stack into the casing when said escapements are operated, each of said escapements having a flange portion adapted to receive the lowermost cup and deliver the same to the dispensing mechanism, and check-controlled means positioned between the internal gear and the feed mechanism whereby both are simultaneously operated.

13. In a vending machine, the combination of a container for a stack of nested cups, a casing associated therewith, a dispensing mechanism in the casing adapted to deliver cups from the casing, and a feed mechanism in the casing between the stack of cups and the dispensing mechanism, said dispensing mechanism comprising a frusto-cone-shaped plug mounted to oscillate, a coin-controlled, annular member mounted to rotate about the axis of the stack, and transmission means from said annular member to said plug, said annular member being adapted to operate simultaneously said plug and the feed mechanism.

14. In a vending machine, the combination of a container having a stack of nested cups, a casing associated therewith, a dispensing mechanism in the casing adapted to deliver cups from the casing, a feed mechanism in the casing between the stack of cups and the dispensing mechanism, and coin-controlled annular members mounted to rotate about the axis of the stack, including means for engaging the feed and dispensing mechanisms for operating the same when said coin-controlled members are operated.

15. In a vending machine, the combination of a container having a stack of nested cups, a casing associated therewith, a feed mechanism in the casing mounted to rotate about the axis of the container and to de-

liver one cup at a time into the casing, and a rotatively mounted dispensing mechanism in the said casing adapted to receive the cups delivered by the feed mechanism, the axes of the said feed and dispensing mechanisms about which they operate being at right angles to each other.

16. Check controlled mechanism including in combination, means for guiding a stack of nested cups in the direction of their common axis, a rotatable ring, means operably connected with said ring for discharging cups from said stack, a second rotatable ring concentric with said first mentioned ring, check connecting means for rotating said first ring from said second ring, a rotatable carriage for receiving and discharging the cups delivered from said stack, and means for rotating said carriage from one of said rings.

17. Check controlled mechanism including in combination, means for guiding a stack of nested cups in the direction of their common axis, a rotatable ring, a second rotatable ring concentric with said first mentioned ring, check connecting means for rotating said first ring from said second ring, a rotatable carriage for receiving and discharging the cups, means actuated by said first ring for delivering cups one at a time to said rotatable carriage, a hand lever for rotating said second ring, and means connecting said second ring with said carriage for rotating said carriage to discharge position by the forward movement of said hand lever.

18. Check controlled mechanism including in combination, means for guiding a stack of nested cups in the direction of their common axis, a pair of concentric rotatable rings check connected for movement together in one direction, and stop connected for movement together in the opposite direction, means operably connected with one of said rings for discharging cups one at a time from said stack, a rotatable carriage for receiving and discharging the cups, and means for rotating said carriage from the other of said rings.

19. Check controlled mechanism including in combination, means for guiding a stack of nested cups in the direction of their common axis, a rotatable ring, a second rotatable ring concentric with said first mentioned ring, check connecting means for rotating said first ring from said second ring, a rotatable carriage for receiving and discharging the cups, means actuated by said first ring for delivering cups one at a time to said rotatable carriage, a hand lever for rotating said second ring, and means connecting said second ring with said carriage for rotating said carriage to discharge position by the forward movement of said hand lever, said cup delivery means being

operable by the return movement of said hand lever.

20. Check controlled mechanism including in combination, means for guiding a stack of nested cups in the direction of their common axis, a pair of concentric rotatable rings check connected for forward movement, means operably connected with one of said rings for discharging cups one at 10 a time from said stack, a rotatable carriage for receiving and discharging the cups, means for rotating said carriage from the other of said rings, and means operably connected with said other ring for returning 15 the several operative parts to their normal positions.

21. Check controlled mechanism including in combination, means for guiding a stack of nested cups in the direction of their 20 common axis, a rotatable ring, a second rotatable ring concentric with said first mentioned ring, check connecting means for rotating said first ring from said second ring, a rotatable carriage for receiving and discharging the cups, means actuated by said 25 first ring for delivering cups one at a time to said rotatable carriage, a hand lever for rotating said second ring, gear teeth on said second ring, gear teeth on said carriage, and 30 and geared means operatively connecting the gear teeth of said second ring and said car-

riage respectively for rotating said carriage from said ring.

22. Check controlled mechanism including in combination, means for guiding a stack of nested cups in the direction of their common axis, a rotatable ring, a second rotatable ring concentric with said first mentioned ring, check connecting means for rotating said first ring from said second ring, 40 a rotatable carriage for receiving and discharging the cups, means actuated by said first ring for delivering cups one at time to said rotatable carriage, a hand lever for rotating said second ring, gear teeth on said 45 second ring, gear teeth on said carriage, and a rotatable member pivotally mounted between said ring and said carriage, said rotatable member having gear teeth in operative engagement with the gear teeth of said ring, and having internal gear teeth in operative engagement with the gear teeth on said carriage for rotating said carriage from said ring.

In testimony whereof I have signed my 55 name to this specification in the presence of two subscribing witnesses.

EMIL A. CLAUS.
